UNITED STATES PATENT OFFICE.

JULIUS BRAUNSTEIN, OF BRONX, NEW YORK, ASSIGNOR TO PREMIER COAL SAVING DEVICE CORPORATION, A CORPORATION OF NEW YORK.

WATER-COOLED GRATE.

Application filed May 22, 1923. Serial No. 640,747.

This invention relates to improvements in water cooled grates as used in connection with coal burning and like furnaces and has as one of its objects to provide a series of 5 hollow grate bars arranged closely adjacent to present a substantially level upper surface for the reception of the fuel and provided with means whereby a constant circulation of water is maintained.

10 Another purpose is to produce water cooled grate, the several bar members of which are interconnected in such manner as to be rigidly held together and mutually support one another, the interengaging elements being water tight so that no leaking can occur.

These and other advantageous objects, such as simplicity, cheapness of construction and ease of assemblage, are accomplished by 20 the novel construction, combination and arrangement of parts hereafter described and shown in the accompanying drawing, forming a material part of this disclosure, and in which—

25 Figure 1 is a perspective view of an embodiment of the invention looking from one of the rear corners, parts being broken away to show the construction.

Figure 2 is a fragmentary bottom plan 30 view of a portion of the grate as assembled, drawn to an increased scale.

Figure 3 is a partial sectional view, taken on line 3—3 of Figure 2 and drawn to a further enlarged scale.

35 Figure 4 is a similar view taken on line 4—4 of Figure 2.

In the drawing the numeral 10 designates in general a hollow rectangular box-like chamber having a floor or bottom 11, end 40 walls 12 and side walls 13, all of which extend to a uniform height; and in one of the side walls is some form of a door or closure (not shown) through which the interior is accessible, as for cleaning or other purposes.

45 The outermost grate bars 14 at the front and rear are of different patterns.

Each of these bars, as shown, consists of a hollow rectangular body closed upon all 50 sides and ends presenting a water space 15 throughout its full length, the same being disposed transversely of the fire box directly upon the end walls 12 of the chamber 10.

55 The upper wall of these box-like bars is extended on adjacent sides, level with the

outer surface as at 16, these flanges being offset downwardly at their edges forming ledges 17, the extensions being strengthened by integral angular braces 18, the length of the ledges being less than that of the bars, 60 stopping uniformly short at each end.

Below the flanged extensions 16, at each end, on adjacent sides of both of the extreme grate bars are relatively short and generally circular projecting bosses 19, the 65 purpose of which will be later described.

The intermediate grate bars 20 are formed in duplicate, each being of the same depth as the bars 14, but relatively narrow, as can be best seen in Figure 3.

70 Their four walls and ends constitute water chambers 21 and their upper walls are extended, as at 22 having braces 23 and provided with ledges 24 corresponding to the extensions 16 and ledges 17 as described.

75 On the opposite side of the intermediate bars are flanges 25 having braces 26, these extensions being suited to seat on the ledges 17 or 24 with which they may be assembled.

80 At each end of the bars 20, below the flange extensions 22 are bosses 27 corresponding to the bosses 19 and on the opposite sides of the bars are other bosses 28, all of these several projecting bosses at one end of the grate being in register and containing 85 conical openings 29 and 30 respectively.

85 These openings are smooth finished to receive push nipples having opposed tapers 31 and 32 fitting tightly and containing central bores 33 through which water may flow 90 from one grate bar to another, the water entering one of the outer bars 14 by the supply pipe 34, passing through the series of bars and out eventually through the pipe 35.

95 These several grate bars are firmly held together by rods 36 passing through the projection or bifurcated ears 37 on the end bars 14, the nuts 37^a drawing the nipples into the conical openings in such manner as to make 100 water-tight joints.

All of the several extending flanges 16, 22 and 25 contain a plurality of openings 38, preferably tapering their bases or larger ends being directed downwardly and open 105 to the chamber 10, into which leads a pipe 39 communicating with a supply of air under pressure.

110 In operation, the grate having been installed in a furnace, to constitute the bot-

tom of its fire box, preferably with the bars extending cross-wise, the fuel may be entered and fire started.

An air blast, supplied by the pipe 39 provides for any required draft and may be controlled in any convenient manner, the air passing out through the perforations 38.

Water under head or pressure entering the pipe 34 is conducted through the series of 10 grate bars, carrying off excessive heat in an obvious manner, the heated water leaving by the pipe 35 for any desired destination.

From the foregoing it will be seen that the grate bars require but three patterns 15 from which plain castings can be made and that the doubly tapered plugs or push nipples if properly fitted, act to prevent leak, hold the bars in place and act as connections from one to another in a simple but efficient 20 manner.

While the foregoing is descriptive of the preferred embodiment of the invention, it will be understood that changes, not conflicting with the scope of the annexed claim, 25 may be made within the general spirit of this disclosure.

Having thus described my invention and

set forth the manner of its construction and use, what I claim as new and desire to secure by Letters Patent is:—

A grate comprising a series of hollow substantially rectangular bars constituting water chambers, laterally extending flanges formed on the respective sides of each bar and extending longitudinally thereof, the upper surfaces of said flanges being flush with the upper surfaces of said bars, a depending ledge formed on the outer longitudinal edge of one of said flanges on one side of each bar for receiving the outer longitudinal edge portion of the flange formed on the opposed side of the adjacent bar, whereby the adjacent longitudinal edges of the adjacent flanges are arranged in abutting relation, bracing means for said flanges, means for communicating the several hollow bars to permit the circulation of water therethrough, and means for clamping the bars together in assembled relation.

Signed at New York in the county of 50 New York and State of New York this 12th day of May A. D. 1923.

JULIUS BRAUNSTEIN.
